Primary Examiner — Susan Bennett Hattan*Assistant Examiner* — Omeed Agilee(74) *Attorney, Agent, or Firm* — Egbert Law Offices, PLLC(57) **CLAIM**

The ornamental design for a gift box, as shown and described.

DESCRIPTION

FIG. 1 is a perspective view of the gift box showing my design.

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is an exploded perspective view thereof.

The broken lines depict portions of the gift box that form no part of the claimed design.

The broken lines in FIGS. 1 and 8 in the shape of an egg depict environmental subject matter that forms no part of the claimed design.
